3 Claims. (Cl. 259—96)

1

This invention relates to a method and apparatus for stabilizing and homogenizing liquid mixtures, such as milk.

Homogenizing machines of the known types with maximum efficiency are so-called high-pressure homogenizers in which the liquid under treatment is forced through very narrow slots under a pressure ranging from 50 to 600 atmospheres. The basic principle in all these machines is to subject the fat- or water-particles to be atomized to such considerable deforming, when they are passing through the narrow slot, that they are divided into a number of smaller particles. As the energy necessary for generating the requisite high pressure can not be recovered, homogenizing machines of this type entail very high operating costs.

Because of this, a great number of other constructions, so-called low pressure homogenizers, have been devised, which work upon very different principles and in which the homogenizing is effected by means of pressures between 1 and 10 atmospheres. The power consumption of these machines is, of course, correspondingly smaller, but their homogenizing effect on the whole also corresponds to the used pressure, so that they can generally be used only for comparatively simple problems. When high requirements must be met in the homogenizing, they can not therefore be used.

The homogenization of milk and cream presents a difficult problem, because in this case an atomization of the fat globules to maximum 2μ and preferably 1μ only, or less, is required. Heretofore it was possible to solve this problem only by means of high pressure homogenizers operated by pressures of at least 50 to 100 atmospheres. Homogenizing of milk has therefore not found the practical and extensive use which could have been expected.

Very comprehensive tests, however, have shown that it is possible to treat milk and cream by means of considerably lower pressures and yet to obtain the same final quality of the product, by abandoning the principle on which the high pressure homogenizers work and to impart instead, in a first step, a comparatively high velocity to the liquid, if possible, without losses and then to treat it in such a way, in a second step, that the velocity is converted, at least largely, into pure liquid friction at highest possible turbulency and avoiding, as far as possible, any friction with the surrounding walls. Tests have shown that, when working on this principle, average diameters of the fat globules ranging from 1.1 to 1.3μ can be obtained, when working with pressures of only 12 to 25 at-

2

mospheres in the homogenizer, according to the invention, while with the best high pressure homogenizers of known types a pressure of 50 to 100 atmospheres would be required for the same purpose. Due to this fact alone the device is of very great importance in practical operation because of the saving of power consumption it enables, but in addition, simple pumps, such as screw pumps, toothed-wheel pumps, and possibly multistage centrifugal pumps, may be used as a source of pressure for the feeding means. Since these pumps have a considerably higher efficiency than the piston pumps which have to be used in the case of pressures of 100 atmospheres and more, a saving of power consumption of 60 to 80 per cent is achieved. Furthermore, it is possible to dispense with the inlet and outlet valves which complicate the use of high pressure homogenizers, so that, taking everything into account, a construction is obtained which, while having the same efficiency, requires only a fraction of the consumption of material and power of piston pumps and is, besides, considerably simpler and can be kept clean and hygienic with less work.

According to the invention, the liquid is supplied from a source of pressure and sprayed into a closed whirl-chamber in which the velocity energy is converted, as far as possible, into pure liquid friction. The dimensions of the whirl-chamber must be determined according to the material to be treated and to prevailing conditions. The higher the pressure at a certain desired effect, the longer the whirl-chamber must be, reckoned in the axial direction of the liquid jet issuing from the nozzle. Its volume and distance from the nozzle are determined by the viscosity of the liquid to be treated. A general rule is that there should only be the lowest possible pressure, that is, a few atmospheres in the whirl-chamber or, if the properties of the liquid make it possible, a pressure approaching nil. If in the case of milk, for example, the homogenizing is considered satisfactory if no cream plugs are formed within 48 hours, a homogenizing device with the following data can be used: pressure 15-30 kgs./cm.², diameter of whirl-chamber 6-12 mms., length of whirl-chamber 50-70 mms., distance between outlet edge of whirl-chamber and liquid outlet of nozzle greater than 4 mms. If, for example, 12 per cent cream is homogenized by means of a higher pressure, the distance should be greater, eventually as much as 20 mms. If a still richer cream is treated, the other data of the whirl-chamber must also be changed and determined according to the viscosity.

The source of pressure may generally be a

screw pump or possibly a toothed-wheel or centrifugal pump. When particularly high requirements are put on the homogenized liquid and when, for one reason or other, the liquid must also be separated, the source of pressure is, according to the invention, the rotating bowl of a separator in which the entire homogenizing device is permanently fitted so that it also rotates. Depending upon the weight of the liquid and the diameter of the separator bowl and its velocity, there is in the outer layer of the bowl a pressure in the order of 30 to 60 atmospheres. After the liquid has passed through the homogenizing device, it discharges into the surrounding vessel so that, in addition to the homogenizing, also a qualitative control of the liquid with regard to particle size can be made in the separator. Fat and water particles of undesirable dimensions are separated in the bowl and fed to the homogenizing device for further treatment. Since the pressure of 30 to 60 atmospheres available in the separator bowl insures a very satisfactory atomization of the particles when homogenizing according to the invention, that part of the liquid flow which has been treated in the homogenizing device may generally be directly mixed with that part of the liquid flow which has passed through the separator.

If it is particularly important for the discharging liquid not to contain particles over a certain size, the liquid issuing from the homogenizing device is returned and mixed with the liquid fed to the separator. By this combination, which is especially advantageous for milk and cream, only part of the whole quantity of the liquid is passed through the homogenizing device, which may be made correspondingly smaller. With a view to avoiding admixture of air, the receiving vessels of the separator should preferably be kept under vacuum.

The effect of the described device may be improved by forcing the liquid out of the nozzle not only with an axial velocity but also with a rotative motion imparted to it in advance of the nozzle by feeding it in a tangential direction into its antechamber. In this manner the velocity gradient is also increased, especially in the whirl-chambers, and the result of the homogenizing is improved. The result of the homogenizing is generally improved as the turbulent motion in the whirl-chamber is increased. Consequently, the result may be improved by providing parts in the whirl-chamber which cause strong turbulence. These parts may, for example, consist of chips or bodies of other shape which are particularly disadvantageous from a flow standpoint, that is to say, are provided with sharp corners, edges, etc. at which whirls are formed. Since such parts can not be kept sufficiently clean, they preferably consist of a single unit which, after completion of the work, can be thrown away and replaced by a new one.

The accompanying drawing shows by way of example some embodiments of the invention.

Fig. 1 is a schematic view illustrating the basic principle of the invention;

Fig. 2 is a similar view, but in greater detail, illustrating the practical construction of an apparatus of this type;

Figs. 3 and 4 are diagrammatic illustrations of a cyclone for increasing the velocity gradient by introducing the liquid tangentially into the apparatus, and

Fig. 5 is a vertical sectional view of a centrifugal separator bowl provided with an homog-

enizing device in accordance with the invention.

The liquid is fed from a nozzle 1 into a whirl-chamber 2 in which the conversion of velocity energy into liquid friction takes place, any friction against the surrounding walls of the bowl-chamber 2 thereby being as far as possible avoided. As shown in Fig. 2, the nozzle 3 is movable in an axial direction in a sleeve 4, so that the distance between the liquid outlet of the nozzle and the outlet edge of the whirl-chamber 5 can be adjusted by a movable part 6. A manometer 7 is used for controlling the pressure in the whirl-chamber. Figs. 3 and 4 show the use of a cyclone 8 for increasing the velocity gradient by introducing the liquid tangentially into the chamber 2 (with a rotating motion about the axis of the chamber). Referring to Fig. 5, from a liquid, which may be fed into the bowl 10 through the hollow spindle or inlet 9, that part which contains fat and water particles of comparatively large diameters is separated in the separating chamber between the discs 11, according to the type of emulsion under treatment. According to the type of emulsion being treated—water in oil or oil in water—the outer (heavier) or the inner (lighter) phase in the separator bowl is led to the homogenizing device 13 for further treatment. From the homogenizing device the liquid flows into the collecting vessel 12, whence it either proceeds to that part which has passed directly through the separator or is remixed with the liquid to be fed to the separator.

In the whirl-chamber 2 (or 5), which may be stationary, the liquid discharged at high velocity from nozzle 1 (or 3) is caused to undergo a whirling motion before it is discharged over the periphery of the whirl-chamber at its open end, as shown by the arrows in Figs. 1 and 2, whereby the liquid velocity is rapidly converted at least largely into liquid friction. It will be understood that when the cyclone 8 is employed to increase the velocity gradient, the cyclone gives the liquid a rotating motion as it passes through the nozzle into the whirl-chamber, as shown by the arrow in Fig. 4. When the homogenizing device is incorporated in a centrifugal separator bowl, as shown in Fig. 5, the homogenizer 13 is essentially the same as those shown in Figs. 1 and 2, in that it has a nozzle for bringing the liquid particles to high velocity, and a whirl-chamber for receiving the nozzle discharge and rapidly converting the liquid velocity (radial) largely into liquid friction before it is discharged into the stationary collecting vessel 12, which preferably kept under vacuum by suitable means (not shown). As illustrated in Fig. 5, the larger particles of the liquid are separated as a lighter component and pass from the central part of the bowl outward through a bottom passage to the nozzle which opens into the whirl-chamber 13 of the homogenizer, the homogenizer being shown only generally in Fig. 5. The heavier liquid from which the larger particles are separated in the bowl passes upwardly under the bowl top and is discharged separately.

I claim:

1. A device for stabilizing and homogenizing liquid mixtures, which comprises a centrifugal separator bowl having an inlet for the liquid and a separating chamber communicating with the inlet, a nozzle in the bowl for receiving the larger particles separated from the liquid in said chamber and operable to bring said particles to high velocity under pressure generated in the bowl, and a whirl-chamber in the bowl com-

municating with the nozzle for rapidly converting the liquid velocity of said particles at least largely into liquid friction with substantial turbulence, to homogenize the mixture of said particles, and a stationary vessel surrounding the bowl for receiving the homogenized particles from the whirl-chamber.

2. Apparatus for stabilizing and homogenizing emulsions, which comprises a centrifugal bowl having a separating chamber for centrifugally separating the emulsion into homogenized and non-homogenized components, the bowl having an outlet for the separated homogenized component, an homogenizing device at the peripheral part of the bowl and having an outlet for a second homogenized component, and means in the bowl for conducting said non-homogenized component from the separating chamber to said homogenizing device.

3. Apparatus according to claim 2, in which the homogenizing device includes a whirl-chamber through which the non-homogenized component passes from said conducting means to said second outlet, the whirl-chamber being

adapted to effect rapid conversion of the velocity of said last component at least largely into liquid friction with substantial turbulence.
